UNITED STATES PATENT OFFICE

ANDREW G. SPINNEY AND CHARLES A. TWIGG, OF PORTLAND, MAINE

SAFETY DEVICE FOR HOT-WATER BOILERS

Application filed April 18, 1928. Serial No. 271,000.

Our invention relates to a safety appliance designed more particularly for use in connection with hot-water tanks or boilers in which water is heated for household purposes.

The primary object of our present invention is to provide facilities for automatically relieving the boiler of excess pressure or to means acting to reduce the temperature of the water therein when either or both rise to the point where injury to the boiler or even a disastrous explosion thereof might occur.

Numerous devices have from time to time been proposed for this purpose, including the ordinary safety-valve, thermostatically controlled valves, fusible plugs and various combinations thereof.

In our safety appliance we have discarded the fusible plug as being unsatisfactory for the reason that it does not respond quickly to slight variations in temperature and have also ascertained, from long experience with these devices, that a single source of relief is not always dependable; we have therefore conceived and constructed apparatus combining the conventional type poppet valve with a novel thermostatically controlled connection therewith, the former taking care of and relieving the boiler from abnormal rises in pressure from any source and the latter affording relief from temperature increases above a safe and predetermined degree, regardless of pressure conditions. The thermostatic elements, by reason of the strength of their expansive properties, are also effective in lifting the valve when for any reason it becomes inoperable due to being stuck on its seat—a prolific source of explosions in hot-water boilers.

It is not now considered good practice in operating high pressure water boilers to place reliance wholly on street mains through which to provide expansible relief from excessive or rising boiler pressures.

In cases where very little hot water is being drawn from the boiler and the heating apparatus,—either a kitchen range or gas heater, is being overworked, the temperature of the water soon reaches a very high point. There is then a conflict between the cold water from the street main and the over-

heated water in the boiler and a violent hammering takes place, sometimes sufficient to cause leaks in the piping system or even to cause a rupture in the boiler itself.

The logical and effective method of alleviating this condition,—in fact to anticipate and prevent it, is to establish a limit in temperature above which it is not feasible to heat the water.

This desideratum is effected in our device by means of the thermostatic control over the temperature of the boiler water brought about by the discharge of more or less of the over-heated water and the admission of cold water from and to the boiler, respectively, resulting in a normal and average temperature being maintained regardless of occasional forced operating of the heating apparatus.

The preferred method of application of our safety device provides for the inclusion of the boiler itself as one of the elements in the thermostat, and utilizing the maximum expansion of the boiler when highly heated supplies a great range in thermostatic movement,—insuring a very sensitive acting relief and positive and quick opening valve.

We have illustrated our invention by the use of the accompanying drawings in which,—

Fig. 1 is an elevation of a hot water tank with our safety device mounted thereon;

Fig. 2 is a fragmentary sectional elevation thereof, drawn to a larger scale, the section being taken on a central, vertical plane through the parts,—the valve being shown in closed position;

Fig. 3 is a sectional elevation of the safety device showing the valve in open position;

Fig. 4 is a fragmentary perspective view of the lower portion of the valve body and the fulcrum arm integral therewith;

Fig. 5 is a perspective view of the lifting beam, and

Fig. 6 illustrates a modified form of the device.

Like parts are identified by similar reference characters.

Referring to the drawings, 1 represents a hot-water boiler mounted on the usual supporting leg 2. The inlet pipe for cold water

supply is at 3, the service hot-water delivery pipe at 4, the pipe carrying hot water from the heater at 5 and the return pipe to the heater, from the boiler, at 6—the foregoing parts all being conventional construction.

Secured to the top portion of the boiler is a flanged fitting 7 directly connected to which is a nipple 8, which, however, might be incorporated as an integral portion of the body or housing 9, to which, as shown, is connected the other end of the nipple 8.

Depending from the side of the housing 9 is a fulcrum arm 10 having at its lower end laterally projecting lugs 10'. Seated on these projections, 10', is the lifting beam 11, the overhanging lips 11' of which directly supporting the beam, and the nipple 8 disposed within the opening 12.

On the short levered end of the beam are bearing ledges 13 upon which rests a nut 14 adjustably secured to the rod 15 which operates through the hole 16 in the beam. This rod extends downwardly and is secured to the bracket 17 fixed on the lower end of the boiler 1. A protecting and insulating sleeve 18 covers the rod 15.

On the opposite, or long levered end of the beam 11 rests the lower end of the valve lifting lever 19, the latter having an offset portion 20 at its top end in which is a hole 21 through which operates the valve spindle 22. A collar 23, pinned on the spindle, serves as means whereby the lever 19 may raise the valve 24 fixed on the lower end of the spindle 22.

The top of the housing 9 is provided with suitable spindle-packing means, as the stuffing-box 25 on the upper end of which is the gland nut 26. A helical spring 27 acts to hold the valve 24 on its seat 28, against the outward pressure of the boiler wafer. The lower end of the stuffing box is screw threaded and adjustable in the housing 9, different adjustments of which serving to provide different degrees of expansive power in the spring 27 which is set to accommodate any particular pressure it is desired to carry in the boiler.

An outlet pipe 29 takes away any water or steam escaping from the boiler when the valve is raised from its seat. A lock ring 30 attached to the housing by the screw 31 prevents turning of the nut 14 after the correct thermostatic adjustment of the rod 15 has been made.

We have also disclosed in Fig. 6 a slightly modified form of safety device, embodying, however, the same principle as the one, the characteristics of which has just been set forth. In this arrangement, the thermostatically responsive element is the pipe 32 which serves as a substitute for the boiler as provided in the construction illustrated in Figs. 1 and 2,—the rod 15, as also the bottom of the pipe 32, being attached to the fitting 33.

Extensions from the pipe 32 to the lower

end of the boiler make circulation possible through this pipe which now serves as the expansible element in the thermostat. It will be observed that the plug 34 used in the former application of the device is now replaced by the nipple 35 through which the hot water passes downwardly through the expansible element 32.

The operation of the safety device is automatic after the proper adjustments are first made. The stuffing-box 25 is first adjusted with reference to the spring 27 to give the latter the required resistance to withstand the pressure to be carried on the boiler. The nut 14 is adjusted to bring all the joints and contacting surfaces of the different parts together—such parts, for instance, as the bearing ledges 13, lugs 10', lips 11' and the two ends of the lifting lever 19. This adjustment is properly done while the boiler is normally heated, after which the nut 14 is relaxed slightly to give the proper lee-way for further expansion of the boiler before the effective action of the thermostat takes place which occurs when further raising of the temperature of the water causes it to function and by raising the valve 24, provide relief from excessive temperature, or excess pressure caused by increased temperature.

In reciting, specifically, the actions produced in the several elements in the thermostatic combination, as disclosed in the construction illustrated in Figs. 1 and 2, we will begin with the boiler itself. It is very unusual to incorporate in this class of apparatus an expansible element of so large proportions as is this boiler, but in this case it provides a very effective agent for the purpose.

When the water temperature increases sufficiently the housing 9 rises with the expansion of the boiler, lifting one end of the beam 11,—the other end being restrained by the rod 15 (see Fig. 3) which being protected from the excessive heat expands inappreciably. The uplift of the beam causes the lifting lever 19 to rise, producing a corresponding upward movement of the spindle 22 and valve 24.

The alternate form of device shown in Fig. 6 operates in principle similarly to the one just described. The pipe 32 is the expanding element, and might, moreover, be considered as a small boiler through which the hot-water circulates; the rod 15 is secured in a manner co-extensively with the pipe 32 and resists the upward movement of the beam 11 when the pipe 32 expands.

Furthermore, it is obvious that the fitting 33 might be attached directly to the bottom end of the boiler 1, in which case the expansible element 32, of the same length as the boiler, is provided with substantially the same characteristics, so far as expansibility is concerned, as obtains in the first style of device described. And, due to the proportions of

the leverage in the lifting beam and the unusual length of expansibility in the expansive member an extremely sensitive and effective lifting action is procured with the least appreciable amount of change in temperature developing in the boiler water.

Should there, from any cause other than from increased temperature, be an increase of gauge pressure within the boiler, the valve 24 is free to act, independently of the thermostatic action of the temperature regulating elements.

The upper chamber *a* in the housing 9 serves as space in which the valve and spring 15 may operate and from the lower chamber *b* a service hot-water pipe (not shown) may extend,—the plug 34, of course, being removed.

Having thus described our invention, what 20 we claim and desire to secure by Letters Patent is:

1. A safety device adaptable for use on hot water boilers, comprising in combination a valve housing having two chambers therein, a 25 partition, having a valve seat thereon, interjacent said chambers, a relief valve operable on said seat, means providing communication between the interior of the boiler and one of said chambers, an escape pipe from the other of said chambers, yielding means acting to seat and hold said valve against the normal water 30 pressure in the boiler, and means, thermally responsive, to open said valve against the force of said seating means when the temperature of the water in the boiler shall have reached a predetermined degree.

2. A safety device for a hot water boiler, comprising in combination a valve housing fixed on the boiler and having therein two 40 chambers, one of which being in communication with the interior of the boiler, a valve seat interjacent the two said chambers, a valve operable on said seat and adapted, normally, to close communication between said 45 chambers, yielding means permitting said valve to open when the pressure in the boiler has risen above a predetermined amount, and thermally responsive means adapted to act to raise said valve from its seat when the 50 temperature of said boiler shall have reached a predetermined degree.

3. A safety device for a hot water boiler, comprising in combination, a valve housing mounted on said boiler and having a chamber 55 therein in direct communication with the interior of said boiler, said chamber having a discharge outlet therefrom, a valve adapted to control said outlet—either to open or close the same, yielding means permitting said 60 valve to open upon the pressure in said boiler reaching a predetermined amount, a lifting beam fulcrumed on said housing, a valve spindle, a lifting lever secured to said spindle and adaptable of actuation by one 65 end of the said lifting beam, and means to

hold the opposite end of said lifting beam substantially immovable when said housing is raised by the expansion of said boiler in response to a rise in the temperature thereof.

4. A device of the character described comprising in combination a water-holding member, a valve housing attached thereto at one end thereof, and having a chamber in direct communication with the interior of said water-holding member, a discharge outlet from said chamber, a valve adapted to control said outlet—either to open or close the same, a lifting lever operably connected to said valve, a lifting beam fulcrumed on said housing and making connection with 70 said lifting lever, means to hold one end of said lifting beam substantially immovable while the other end is raised in response to the expansion of said water-holding member, whereby communication may be established 75 between the interior and the outside of said water-holding member.

5. A device of the character described comprising in combination a water-holding member, a valve housing, having a chamber 90 therein, secured to said member, said chamber being in direct communication with the interior of said water-holding member and having a discharge outlet therefrom, a valve adapted to control the passage of water from 95 said water-holding member through said outlet, expansible means acting on said valve to close said outlet, means to vary the expandable force applied to said valve to close said outlet, a valve spindle fixed on said valve, a 100 lifting lever attached to said spindle, a lifting beam fulcrumed on said housing and making connection at one of its ends with said lifting lever, a rod, disposed in separated relation to said water-holding member, 105 adjustably secured to the other end of said lifting beam, and means to fixedly secure the opposite end of said rod to said water-holding member.

In testimony whereof we affix our signatures.
